Attorney

UNITED STATES PATENT OFFICE.

JAMES A. GREER, OF SAN FRANCISCO, CALIFORNIA, ASSIGNOR TO THE RAIL JOINT COMPANY, OF NEW YORK, N. Y., A CORPORATION OF NEW YORK.

RAIL-JOINT.

1,232,286.

Specification of Letters Patent.

Patented July 3, 1917.

Application filed April 7, 1916. Serial No. 89,694.

To all whom it may concern:

Be it known that I, JAMES A. GREER, a citizen of the United States, residing at San Francisco, in the county of San Francisco and State of California, have invented 5 certain new and useful Improvements in Rail-Joints, of which the following is a specification.

This invention relates to rail joints, and 10 more particularly to an improvement in joints of the character adapted to high T rails.

Primarily the present invention contemplates a supplemental strengthening unit 15 for rail joints, and although fundamentally useful in connection with joint bars for rails known as the high T type, generally utilized in street railway construction, the invention may also be employed in connection with 20 joint bars of other types where it is desired to strengthen or reinforce the same. Furthermore, this improvement is intended to possess special utility in its application to used rail joints.

Accordingly, the present invention has in view a novel auxiliary construction for rail joints, whereby the strength of joint bars in use may be materially augmented, while at 25 the same time the entire efficiency of the joint increased by providing a base support for the rails, thus giving renewed stability at a minimum cost. In this connection, it will be apparent that the invention is of practical and economical importance, since 30 it makes provision for increasing the life and strength of used rail joints.

With the above and other objects in view which will more readily appear as the nature of the invention is better understood, 35 the same consists in the novel construction, and the combination and arrangement of parts hereinafter more fully described, illustrated and claimed.

A preferred and practical embodiment of 40 the invention is shown in the accompanying drawings in which:

Figure 1 is a vertical transverse sectional view taken at the end of a rail joint on a high T rail showing the application of the 45 present invention thereto.

Fig. 2 is a view similar to Fig. 1 showing the application of the invention to an ordinary rail joint.

Similar references designate correspond-

ing parts throughout the several parts of 55 the drawings.

In Fig. 1 of the accompanying drawing there is shown a rail R of the conventional high T type, having the usual type angle bars A and B at each side thereof to constitute with the bolts C and D, the usual joint for connecting the rails. Under severe traffic conditions, and particularly in certain locations in a track, rail joints of the character specified require added strength and 60 stability and the present invention therefore proposes to accomplish this desirable result by the use of a supplementary strengthening unit which may be readily applied to the joint without alteration thereof. The 65 said supplementary strengthening unit primarily includes a shoe angle member 1, of the well known Weber type, which comprises an upstanding vertical web member 2 and a horizontal base member 3, the latter 70 member being adapted to underlie the rail ends. In addition to the metal shoe angle the strengthening unit utilizes a wooden or 75 equivalent compressible filler block 4, preferably of a reversible type. And this filler 80 block is arranged at the inner side of the upright member 2 of the shoe angle.

In order to complete the supplementary strengthening unit and render the same entirely effective for its intended purpose there 85 is combined with the compressible filler block 4 a metal guard plate designated by the numeral 5. This guard plate is adapted to be arranged over the inner side of the filler member so as to be interposed between 90 the latter and the outer side of one of the joint bars, so that when the joint bolts are tightened up the filler member will be clamped under compression between the upright member of the shoe angle and the side 95 guard plate, and the latter will be directly and rigidly clamped against the outer side of the said splice member. It is by reason of this particular relation of parts that the said supplementary strengthening unit 100 greatly adds to the strength and stability of the used joint, and with further reference to the metal guard plate 5 it will be observed that the same is provided at its upper and lower edges with the outturned inclined holding flanges 6 and 7 respectively, 105 which flanges have an engagement with and fit the correspondingly inclined or beveled

faces 8 and 9 respectively of the wooden or equivalent compressible filler 4. This formation provides a guard plate of the channeled form, the channel of which snugly 5 registers with one side of the compressible filler, and the upper holding flange 6 subserves the function of a restraining element to prevent the compressible filler from being crushed and distorted out of shape through 10 the turning of the joint bolts. In connection with the mounting of the channel guard plate 5 a further feature of the invention resides in forming said plate with the bolt holes 10 and 11 adapted to align with the 15 bolt holes in the various other parts of the joint, and which bolt holes 10 and 11 are approximately the diameter of the bolts themselves so as to closely fit the latter whereby the bolts serve to retain the guard 20 plate firmly in position so that it will effectively perform its function as a protecting member for the compressible filler.

The application of the invention to an ordinary rail joint of the angle bar type is 25 shown in Fig. 2, and in this construction it will be observed that all the essential features shown in Fig. 1 are adhered to. In this form of the invention the rail is designated as R', and has the usual type angle 30 bars A and B at each side thereof to constitute with a single line of bolts C' the usual joint for connecting the rails. Like the form of the invention shown in Fig. 1, the supplementary strengthening unit is arranged at one side of the joint and essentially comprises the angle shoe 1 having the 35

vertical web member 2 and horizontal base 3, said vertical member 2 coöperating with a filler block 4 and metal guard plate 5 in the same manner that the similar parts do in 40 the construction shown in Fig. 1.

The construction described not only secures the desirable results referred to, but the utilization of the compressible filler in the combination specified contributes to the 45 resiliency of the joint and imparts to the latter some of the well known characteristics of the Weber type of rail joint which employs a filler of that character.

I claim:

1. A supplementary strengthening unit for rail joints comprising, in combination with the joint bars and the joint bolts, a shoe angle, a filler block arranged at the inner side of the shoe angle, and a guard 55 plate interposed between the filler block and one of the joint bars.

2. In a rail joint, the combination with the rails, the joint bars and the joint bolts, of a supplementary strengthening unit comprising a shoe angle, a filler block, and a guard plate, the said guard plate closely fitting the bolts and having holding flanges at its upper and lower edges to engage the 60 filler block.

In testimony whereof I hereunto affix my signature in the presence of two witnesses.

JAMES A. GREER.
